(57) CLAIM

The ornamental design for a headband with attached holder for hair as shown and described.

DESCRIPTION

FIG. 1 is a perspective view of a headband with attached holder for hair of the present design, shown being worn by a user;

FIG. 2 is a perspective view of the headband with attached holder for hair shown in an alternate configuration without a user.

FIG. 3 is a right-side view thereof.

FIG. 4 is a left-side view thereof.

FIG. 5 is a rear perspective view thereof.

FIG. 6 is a front perspective view thereof.

FIG. 7 is a top plan view thereof.

FIG. 8 is a bottom plan view thereof; and,

FIG. 9 is a top perspective view of the headband with attached holder for hair, as shown being worn by a user with the portion of the attached holder for hair in a rolled-up configuration.

The partial human figure outlined by broken lines assists to illustrate the headband with attached holder for hair in a position of use and forms no part of the claimed design.

1 Claim, 9 Drawing Sheets
